UNITED STATES PATENT OFFICE

CLIFFORD E. HARRISON, OF PHILADELPHIA, PENNSYLVANIA, ASSIGNOR TO AMERICAN ENGINEERING COMPANY, OF PHILADELPHIA, PENNSYLVANIA, A CORPORATION OF PENNSYLVANIA

AIR REGULATOR FOR TUYÈRES

Application filed October 29, 1929. Serial No. 403,244.

The principal object of this invention is to provide a novel and desirable means for controlling the volume of draft air passing to the individual elements of a furnace tuyère.

5 In mechanical stokers, and particularly in stokers of considerable length, maintenance of a uniform depth of fuel throughout is difficult, there being a tendency for the fuel bed to thin out at the rear end. For this reason 10 and because the fuel requires different volumes of draft air for maximum efficiency in the different stages of combustion, it is highly desirable to provide means for controlling the flow of air to different sections or areas of the 15 fuel bed. By the herein described invention, I have provided a device of extreme simplicity whereby the flow of air to the individual tuyère elements or blocks may be accurately controlled, said means being readily adjustable to vary the air supply as required.

In the attached drawing:

Figure 1 is a side elevational view of a section of tuyère comprising three superimposed tuyère blocks or elements and including air-controlled devices made in accordance with the present invention;

Fig. 2 is a rear elevational view of the tuyère section shown in Fig. 1; and

30 Fig. 3 is a view in perspective of the air-controlled device forming the subject of the present invention.

With reference to the drawing, Figure 1 shows a section of a tuyère of an inclined 35 stoker employing tuyère elements or blocks of standard form. In the normal operation of the stoker, air is supplied to the tuyères and to the individual tuyère elements from below the tuyère and through the open rear 40 ends of the said elements, this space being enclosed and constituting the wind box of the furnace. As illustrated, each of the tuyère blocks designated by the reference numeral 1 is provided with a rear extension 2 45 in the form of a flat flange, which extensions

in assembly define the rear or open ends of the tuyère elements.

In accordance with the present invention, I mount upon the rear ends of each of the extensions 2 a member 3 which constitutes in each instance a means for controlling the volume of air passing to the next higher tuyère elements. As shown in Fig. 3, the member 3 takes the form in the present instance of a metallic clip adapted to embrace 55 and resiliently grip the rear ends of the flanges 2, see Fig. 1, each clip comprising an upstanding flange 4 composed of a plurality of closely arranged independent fingers 5. As illustrated in Figs. 1 and 2, these fingers 60 5 project upwardly from the tops of the rear extensions 2 towards the under side of the corresponding extension of the next higher tuyère element, and thereby tend to obstruct the openings into the interiors of the individual tuyère elements through which the air supply enters these elements. With all of the fingers 5 in the upright position as illustrated in Fig. 3, there is obviously a maximum obstruction and interference to the entrance of the draft air. By bending down the tongues 5 or various ones thereof, the obstruction may be modified as required to give the individual tuyères the required relative proportions of draft air. In Fig. 2, it will 70 be noted that more of the fingers 5 are turned down in the lower members than in the upper whereby a greater volume of air is permitted to enter the lower tuyère cavities than the upper ones. The tongues 5 being small and 75 relatively large in number makes possible a close adjustment of the air entering the tuyère elements.

Flexible metal has been found best suited for the manufacture of these elements, this 85 having the necessary resiliency to frictionally grip the tuyère parts to which they are attached and also permitting bending down of the tongues 5 to an inoperative position without difficulty. It will be noted that the ele- 90

ments are somewhat shorter in length than the width of the tuyère block rear extensions to which they are attached. This is not essential, but is a desirable precaution, since at no time in normal operation is it desirable to entirely eliminate air from any section of the tuyère.

It is to be understood that form of the member 3 may vary considerably from that shown without departure from the invention.

I claim

1. A tuyère comprising a plurality of cavities constituting passages for draft air and having rearward extensions intermediate said cavities, and resilient metallic clips frictionally gripping said extensions and comprising a plurality of displaceable extensions projecting across the mouths of said cavities and constituting a means for controlling the flow of draft air through the passages.

2. In a furnace, a tuyère having a passage for draft air, a rearward extension on said tuyère, means mounted on said extension for controlling the flow of draft air through the said passage, said means comprising a plurality of members adapted to be adjusted to one position to obstruct the flow of air through said passage and to another position when it is desired to pass a greater amount of air through said passage.

3. In a furnace, a tuyère provided with a passage for draft air, a rearward extension on said tuyère, and a member adapted to be attached to said extension and having a plurality of individual elements adapted to be adjusted between vertical and horizontal positions to regulate the amount of air passing through said passage.

4. In a furnace, a tuyère comprising a plurality of cavities constituting passages for draft air, rearward extensions intermediate said cavities, and means mounted on said extensions comprising a plurality of elements independently adjustable to control the flow of air through said cavities.

5. An article of manufacture comprising a metallic clip adapted to frictionally engage a rearward extension of a tuyère, said clip having a plurality of individual elements adapted to be adjusted between alternative positions to control the amount of draft air passing through said tuyère.

6. An article of manufacture comprising an air regulator formed from suitable sheet material having means thereon for engaging a furnace tuyère, and a plurality of independently adjustable elements for regulating the flow of air through said tuyère.

7. An article of manufacture comprising an air regulator formed from flexible sheet material having means thereon for engaging a furnace tuyère, and a plurality of flexible elements independently adjustable to regulate the flow of air through said tuyère.

8. In a device of the class described, a

tuyère provided with a passage for draft air, and means adapted to be attached to said tuyère, said means comprising one or more elements adapted to be adjusted to regulate the amount of air passing through said passage.

9. An article of manufacture comprising an air regulator formed of suitable sheet material having means thereon for securing the same to a furnace tuyère, and one or more adjustable elements for regulating the flow of air through said tuyère.
